[57] CLAIM

The ornamental design for a fly box, as shown and described.

DESCRIPTION

FIG. 1 is a perspective view of a fly box showing my new design with the box portion pulled down and the lid partially opened;

FIG. 2 is a top plan view of the fly box in the closed position;

FIG. 3 is a front elevational view of FIG. 2;

FIG. 4 is a bottom plan view thereof;

FIG. 5 is a left side elevational view the opposite side being a mirror image thereof;

FIG. 6 is a rear elevational view thereof; and

FIG. 7 is a top plan view thereof with box portion tilted out.

FIG. 1

FIG. 2
